UNITED STATES PATENT OFFICE

113,144

DESIGN FOR A CHAIR OR SIMILAR ARTICLE

Kurt Meitner, Shaker Heights, Ohio, assignor to Sun Radiator Cover Company, Inc.

Application November 12, 1938, Serial No. 81,057

Term of patent 3½ years

To all whom it may concern:

Be it known that I, Kurt Meitner, a citizen of the United States, residing at 2884 Woodbury Road, in the city of Shaker Heights, county of Cuyahoga, and State of Ohio, have invented a new, original, and ornamental design for a Chair or Similar Article, of which the following is a specification, reference being had to the accompanying drawing, forming a part thereof.

The dominant features of the design are shown in full lines.

I claim:

The ornamental design for a chair or similar article, substantially as shown and described.

KURT MEITNER.
